John C. Yerkes, Philadelphia, Pa., assignor to
John C. Yerkes and Jack Alloy, both of Phila-
delphia, Pa., a partnership

Application November 4, 1935, Serial No. 59,381

Term of patent 7 years

To all whom it may concern:

Be it known that I, John C. Yerkes, a citizen of the United States, residing at Philadelphia, in the county of Philadelphia and State of Pennsylvania, have invented a new, original, and ornamental Design for a Paper Weight or Similar Article, of which the following is a specification, reference being had to the accompanying drawing, forming part thereof.

In the drawing:

Fig. 1 is a front elevational view of a paper weight or similar article showing my new design.

Fig. 2 is a side elevational view.

Fig. 3 is a rear elevational view of Fig. 1.

Fig. 4 is a side elevational view opposite to the side shown in Fig. 2.

I claim:

The ornamental design for a paper weight or similar article, substantially as shown.

JOHN C. YERKES.
